DESIGN FOR A SETTEE

Andrew L. Henkel and Burke M. Ewing, Chicago, Ill., assignors to The Brunswick-Balke-Collender Company, Chicago, Ill., a corporation of Delaware

Application December 2, 1940, Serial No. 97,002

Term of patent 14 years

To all whom it may concern:

Be it known that we, Andrew L. Henkel and Burke M. Ewing, both citizens of the United States, both residents of the city of Chicago, in the county of Cook, State of Illinois, have invented a new, original, and ornamental Design for a Settee, of which the following is a specification, reference being had to the accompanying drawing, forming a part thereof.

We claim:
The ornamental design for a settee, as shown.

ANDREW L. HENKEL.
BURKE M. EWING.
